UNITED STATES PATENT OFFICE.

JEAN M. H. P. MÉTIVIER, OF PARIS, FRANCE.

IMPROVEMENT IN PUMPS.

Specification forming part of Letters Patent No. 38,117, dated April 7, 1863.

To all whom it may concern:

Be it known that I, JEAN MARIE HENRI PAUL MÉTIVIER, of Paris, in the Empire of France, have invented certain new and useful Improvements in Pumps; and I hereby declare that the following is a full, clear, and exact description of the same, reference being had to the accompanying drawings, to be hereinafter referred to.

The characteristic feature of my invention of improvements in pumps is the employment of two shafts, together with inclined pump-barrels and pistons, as hereinafter explained. One of the shafts is inclined at any desired angle, and the two shafts are coupled together by a universal or other joint insuring the same speed to both, and causing them to revolve in the same direction. One of the shafts carries, through a horizontal disk or cross-bars, a pair or more of pump-barrels, set at the same angle as the inclined shaft, while the other (say the inclined shaft) has fixed on the lower part an inclined cross head, with rods and pistons also inclined to correspond with and work in the pump-barrels. A vessel or case fitted with a cover which may be removed when required has a suction pipe fitted at the lower and a discharge-pipe at the upper part. Both pipes are provided with suitable valves, and in this vessel the barrels and pistons are inclosed. The pump-barrels (say three) are suspended from the under side of the horizontal disk or cross-bars in such manner as to be able to adapt themselves to the inclinations of the pistons. A ring of some strong flexible material unites and keeps the pumps water and air tight, so that the top of the pump-barrels is in communication with the discharge, while the bottom of the pumps is in communication with the lower part of the vessel. A diaphragm may, if desired, surround the lower part of the plate.

Figure 1 of the accompanying drawings is a vertical section, and Fig. 2 is a horizontal section, of a pump fitted with three barrels according to my invention.

A is a metal or wood case inclosing the pumps.

B is a cover secured to the case by bolts or screws, and in such manner that it may with facility be removed when required.

C is the suction-pipe, and D is the discharge-pipe, the latter being provided with a stop-valve.

The two shafts M N are united at the point O, and have a continuous or alternate rotary

motion imparted to them by means of a crank, X', pulley, toothed wheels, or other appliance for communicating motive power.

H is a plate, keyed to the shaft M, and made tight by packing, a, inserted in a groove formed in its flange. To this plate three pump-barrels, F, are attached, each barrel being free to move about the points I through universal joints, so that they may assume any inclination, according to the motion of the pistons. A diaphragm, L, is secured to the plate H, and surrounds the barrels of the pumps, so as to check the agitation of the water around the outside of the barrels. The upper end of the barrels is enlarged, and over this enlargement leather washers K are placed and secured to the plate H. The washers have sufficient play to allow of their moving with the barrels.

P is a cross-bar, fixed to the second or inclined shaft, N, and to which the pistons Q are fixed. These pistons are fitted clapet or spherical valves h, or with any other suitable valves. The piston-rods are parallel with the shaft N, and are set at an equal distance from its axis.

On motion being communicated to the shaft M, similar motion is transmitted to the lower shaft, N, to the plate H, barrels F, and pistons Q. If at the commencement of rotation one piston were at the bottom of one barrel, and the opposite piston at the top of the opposite barrel, then, upon the completion of a semi-rotation, that which was at the top would have become at the bottom of the barrel, and vice versa. As the barrels move, or as the pistons move in the barrels, so air, water, or other liquid is drawn into and discharged from pump. The action is similar, whether the shafts receive a continuous rotary motion in one direction, or an alternate rotary motion.

Having now described the nature of my invention, and in what manner the same is to be performed, I declare that I claim—

The employment, in pumps, of two shafts jointed together, and of inclined pump-barrels and pistons, all being fitted and caused to act substantially as hereinbefore described, and illustrated in the accompanying drawings.

In testimony whereof I have signed my name to this specification before two subscribing witnesses.

J. M. H. P. MÉTIVIER.
